Primary Examiner — Robert M. Spear*Assistant Examiner* — Kendra Leslie Hamilton(74) *Attorney, Agent, or Firm* — Adam K. Sacharoff; Much Shelist, P.C.(57) **CLAIM**

The ornamental design for a lid for a pan, as shown and described.

DESCRIPTION

FIG. 1 is a top front perspective view of a lid for a pan, showing our new design;

FIG. 2 is a left side view thereof;

FIG. 3 is a right side view thereof;

FIG. 4 is a front view thereof;

FIG. 5 is a rear view thereof;

FIG. 6 is a top plan view thereof;

FIG. 7 is a bottom plan view thereof; and,

FIG. 8 is a bottom perspective view thereof.

The broken lines in the drawings represent unclaimed portions of the lid for a pan and form no part of the claim.

1 Claim, 5 Drawing Sheets(56)
